UNITED STATES PATENT OFFICE.

WILLIAM D. BUTT, OF KANSAS CITY, MISSOURI.

ADVERTISING DEVICE.

No. 887,766.

Specification of Letters Patent. Patented May 19, 1908.

Application filed August 31, 1903. Serial No. 171,383.

To all whom it may concern:

Be it known that I, WILLIAM D. BUTT, a citizen of the United States, residing at Kansas City, in the county of Jackson and State 5 of Missouri, have invented a certain new and useful Improvement in Advertising Devices, of which the following is a specification.

The present invention relates to a display or advertising device, or sign, and has for its 10 object to produce a new and improved device of this description.

My invention is illustrated in the accompanying drawings, wherein,

Figure 1 is a view of a device embodying 15 my invention, parts being broken away to show the interior; Fig. 2 is a view of the device with the top removed showing the interior; Fig. 3 is a sectional view taken on line 3—3 Fig. 1; Fig. 4 is a view showing one 20 form of moving device associated with the sign or device to be displayed; Fig. 5 is a plan view of a portion of the bottom of the illuminated chamber; Fig. 6 is a detailed view showing the means for holding the display 25 panel in place; Fig. 7 is a perspective view showing a portion of one form of color producing or transmitting device; Fig. 8 is a detailed view showing one of the controlling switches.

30 Like letters refer to like parts throughout the several figures.

Referring now to the drawings wherein is illustrated one form of device embodying my invention there is provided a case A which 35 may be of any suitable design, shape or configuration. This case is preferably provided with two chambers A¹ and A², the chamber A¹ being what may be termed the display chamber and the chamber A² forming an 40 illuminated chamber. This latter chamber is preferably opaque. The case A is provided on one or both sides with a panel A³ which is preferably transparent and may, for example, consist of a piece of glass. This 45 panel is preferably attached to the case so as to be movable. This may be accomplished, for example, by mounting it in, or upon, a frame A⁴ which is hinged in any suitable manner to the case, as for example, by the projections A⁵ which extend into suitable openings in the case or some part associated therewith. These panels therefore form one or both sides of the display chamber. Associated with the panel is a sign of any desired 50 description and when I use the term "sign"

I use it to designate any character, or characters, or design or display device. This sign which is shown in the figure as a locomotive B may be associated with the panel A³ in any desired manner. It may, for example, be affixed to the face of the panel or it may be held in proximity to the panel. In the drawing I have shown it as affixed to the panel. In this particular case the body of the locomotive is made opaque in any suitable manner while the portion where the driving wheels are located is arranged so as to be pervious to the light as by being made transparent or translucent. In describing this device the word "transparent" will be 60 used but when used it is understood to mean any material pervious to the rays of light. Back of the wheels of the locomotive I provide a moving device consisting in the present instance of the wheels B¹, one of said 65 wheels being back of each of the driving wheels of the locomotive. These wheels are rotated in any desired manner so that when the interior of the display chamber is illuminated the rays of light passing through the 70 transparent portion of the sign are interrupted so as to make it appear that the wheels of the locomotive are actually rotating. This illusory effect would of course be 75 different in different signs but it would be 80 produced in substantially the same way, viz., by placing back of that portion of the sign to which it is desired to give the appearance of movement, a suitable moving device for intercepting the rays of light.

90 Associated with the stationary part of the sign is a movable part C which in this case is shown as a portion of a landscape, but it is of course evident that this movable part may be any suitable representation which will 95 harmonize with the stationary part of the sign. The movable part C may be arranged in any desired manner and when in movement will aid in the illusory effect and give the locomotive the appearance of movement. 100

As herein shown, the part C is an endless sheet mounted upon rollers C¹ which are carried by the shaft C² rotated in any desired manner. I may also locate beneath the stationary part of the sign a second movable 105 part C³ which is mounted upon rollers C⁴ in a manner similar to that described with relation to the movable part C. As herein shown, the movable parts C & C³ are placed back of the panel A³ and may be of any de- 110

sired dimension or arrangement, but preferably arranged so that the edges will project past the stationary part of the sign, thus doing away with any intervening space which would be detrimental to the appearance of the device.

The illuminated chamber A² may be lighted in any desired manner. As herein shown, it is lighted by means of the lamps D which are arranged to throw the light into the display chamber. This result may be secured by coating one face of the lamp with some suitable material or by locating mirrors, or the like, above the lamps. The illuminated chamber is preferably provided with a partition, or bottom, E which is provided with an opening E¹ (see Figs. 3 & 5) through which light is thrown into the display chamber. This bottom is also provided with the slots or elongated openings or apertures E², located so that the light passing therethrough is projected along the outer faces of the panels A³. A motor F is located in the illuminated chamber and is connected by suitable gearing with the shaft C² so as to rotate it and thus transmit motion to the movable parts C & C³.

There is preferably associated with the sign, means for producing effects by means of colored light. These effects may be of various kinds, such as the changing of the appearance of the sign, or a portion thereof, by changing the color of the light and by representing various conditions, such as daylight, twilight, moonlight, and the like. This may be accomplished, for example, by providing above each opening E² a movable frame G containing a series of plates of different colored glass. It will be seen that when these devices are in one position, the light passing through the openings E² will take on a color similar to the glass plate through which it passes, and by rotating these devices, the different plates may be brought between the source of light and the openings E². It will thus be seen that various color effects may thus be produced. It is of course evident that any desired number of plates may be placed in the frame. These frames may be rotated in any desired manner, as for example, by connecting them with the motor F. As shown in the drawings, they are connected with said motor by means of worm wheels but it is of course evident that any other suitable mechanism may be used. It is of course evident that the illuminated chamber and the apertures E² may be located in any desired position. I also prefer to place within the display chamber a modifying device for modifying the visual or display effect, and which, as illustrated, consists of a series of different colored lights H, such as red, white, blue, and the like. These may be lighted either singly or in any desired combinations so as to produce any desired color effect.

These colored lights, illuminating the back of the sign, will bring out in relief, as it were, in the various colors, portions of the sign through which the light passes and it will be seen that this arrangement is capable of extended and effective use.

The motor F may be used to drive the moving device B¹, as for example, by means of the belt F¹. This belt, as shown, passes around a pulley on a shaft which is driven from the upright shaft, C², by worm gearing. This moving device is supported on a suitable frame B². The locomotive is preferably provided with a headlight I and this may be made to be alternately lighted and extinguished so as to flash out, as it were, at intervals by means of a suitable switch, such as that shown in Fig. 8, which consists of a rotating wheel I¹ provided with a series of contacts I² connected to a central part I³ which is connected in the electric circuit, there being provided a stationary contact I⁴ also connected in the circuit. The wheel is rotated by the motor F and it will thus be seen that it alternately makes and breaks the circuit through the lamp I. When this device is used the sheet C will have to be sufficiently pervious to light so that the light from the lamp I will shine through to make the representation of the head light.

This device is of course capable of being used for 24 hours in a day. It is of course evident that it should be so located when it is used in the day time as to prevent the glare of the daylight from over-powering or counteracting the illumination from within and thus decreasing the effect desired to be produced. It is also evident that any means for protecting the sign from the glare of the daylight may be used, such for example as a shielding or shadow producing frame, or the like. Such matters will of course depend upon the conditions to be met with.

I have described in detail a particular construction embodying my invention but it is of course evident that the parts may be greatly varied in form, construction and arrangement and that some of the parts may be omitted and others used with parts not herein shown without departing from the spirit of my invention. I therefore do not limit myself to the particular construction shown and described.

The part representing the smoke from the locomotive is made pervious to the rays of light and the moving part back of it causes the smoke to appear to be moving.

The use and operation of this invention are as follows: When the device is to be displayed the chamber A² is illuminated and the movable parts C & C³ of the sign are set in motion by the motor or through any other desired agency. The moving device B¹ is also set in motion. The light from the illuminated chamber passes down through

the opening E¹ into the display chamber and the transparent portions of the sign permit the light to pass out, so as to secure the proper illuminating effect. The moving device B¹ produces an appearance of motion in the wheels of the locomotive while the movable parts C & C³ give the locomotive the appearance of moving.

The colored light passing through the openings, or apertures, E² light up the outer face of the sign so as to produce the effect desired and this effect may also be produced, or assisted, or modified, by the colored lights H. It will be seen that by this arrangement any desired color effect can be produced. It will also be seen that the various illusory effects can be produced by this device and that it may be applied in various ways and for various purposes. The lights H may be controlled by a suitable switch or controlling device such as that shown at H¹.

I claim:

1. An advertising device comprising a stationary part and a movable part, said stationary part comprising a transparent panel with a translucent design affixed thereto, said movable part located behind the design, and means for moving said movable part so as to give the design portion thereof the appearance of movement.

2. An advertising device comprising a stationary part and a movable part, said stationary part comprising a transparent panel with a translucent design affixed thereto, means for moving the movable part along the stationary part so as to give the stationary part the appearance of movement, and a

device for illuminating both sides of said design.

3. An advertising device comprising a case provided with a transparent panel, a sign associated with said panel comprising a stationary part and a movable part, which parts harmonize to produce a unitary effect, and means for moving the movable part along the stationary part.

4. An advertising device comprising a case provided with a transparent panel, a sign associated with said panel comprising a stationary part and a movable part which harmonize in producing a unitary effect, a device for illuminating said panel from within, and means for throwing light on the outer face of said panel so as to vary the effect produced.

5. An advertising device, comprising a case provided with a transparent panel, a sign associated with said panel, comprising a stationary part provided with a portion previous to rays of light, means for illuminating the back of said sign so that the light passes through the previous portion, a device associated with said stationary part for intermittently intercepting the rays of light so as to produce an illusory effect of motion in a portion of the stationary part, and a movable part forming a significant element in the sign and adapted to harmonize with the stationary part so as to produce an appearance of motion in the stationary part.
